UNITED STATES PATENT OFFICE.

EMANUEL W. HARTMAN, OF LOS ANGELES, CALIFORNIA, ASSIGNOR TO HARTMAN INTERESTS, INC., OF LOS ANGELES, CALIFORNIA, A CORPORATION OF NEVADA.

CRACKING APPARATUS.

Application filed June 9, 1923. Serial No. 644,379.

This invention relates to an improvement in a cracking apparatus whereby the apparatus can be operated continuously and the material from which some gasoline has been derived is retreated; such invention being applicable to the obtaining of gasoline from low grade petroleum oils or from any petroleum oil or residue containing hydrocarbons the term "crude oil" being used herein to include all such materials.

The chief object of this invention is to provide an apparatus which can be continuously operated for cracking crude oil in contradistinction to cracking apparatus which can be used only for cracking one batch of crude oil and must then be prepared for another batch.

In accomplishing the objects of this invention I provide, in a typical apparatus, a cracking apparatus comprising two high pressure stills in which the crude oil is heated first to 725° F., and then to 900° F., two retorts into which this heated oil is forced under pressure of approximately 600 lbs. per square inch against hot plate crackers and a chamber to which the gasoline cracked from the oil passes from both the stills and retorts and in which it is collected and fed to the gasoline condensers.

I also provide in carrying out my invention, in the stills of this apparatus revolving means by which the crude oil being heated is continuously agitated to hasten cracking, by which the formation of carbon crusts on the walls of the stills is prevented, and by which the sediment is forced into a sump from which it is drawn off; and provide in the retorts a revolving means, and at one end of each of these retorts a trap, the revolving means preventing the formation of crusts on the walls of the retort and feeding this crust to the traps.

Other objects and accomplishments of the invention reside in the details of construction and will appear from a consideration of the following specification of preferred forms of apparatus and process, reference being had for this purpose to the drawings which form a part thereof, and in which—

Fig. 1 is a side elevation of this apparatus.

Fig. 2 is a front elevation;

Fig. 3 is a cross section taken along the line 3—3 of Fig. 1; the agitators in the stills and retorts being omitted;

Fig. 4 is a cross section taken along the

line 4—4 of Fig. 1, the cover of one of the stills being removed to show an end view of the agitator;

Fig. 5 is an enlarged section of the nozzle by which the heated crude oil is sprayed into the retort;

Fig. 6 is an enlarged cross section of the end of one of the stills, showing the method of preventing the escape of any oil around the revolving shaft which forms a part of the agitator;

Fig. 7 is a detailed view of one of the traps, by which the sediment is removed from one of the stills;

Fig. 8 is a transverse section taken along the line 8—8 of Fig. 4.

Fig. 9 is a rear view of the apparatus;

Fig. 10 is a side elevation of the rear end of the apparatus, this figure forming with Fig. 1, a side elevation of the complete apparatus; and

Fig. 11 is a sectional view of the valve which controls the escape of the cracked gasoline from the chamber to the condenser.

Referring to the drawings, the reference number 20 is used to designate the cracking apparatus as a whole, which apparatus comprises the high pressure stills A; the retorts B, the collecting chamber C, and the parts appurtenant therewith, all enclosed within the walls of a furnace D. The two stills A and the two retorts B are identical in construction and only one of each will therefore be described; the same reference numerals, however, being used on both.

The still A is of cylindrical formation, being preferably composed of a metal tube 21 having flanges 22 and 23, at each end and closed by means of caps 24 and 25, which are also provided with flanges 26 and 27, similar in formation to the flanges 22 and 23. The caps 24 and 25 are secured to the tube 21 by means of bolts 28 which pass through the flanges 22, 26 and 23, 27 respectively. In order to seal the space between the flanges, suitable packing 29 may be employed. In the cap 25 is formed an aperture 30, defined by an outwardly projecting boss 31 and inwardly projecting boss 32. The boss 32 is preferably braced by suitable fins 33 integral therewith. Through the aperture 30, and the bosses 31 and 32 extends a shaft 34 which actuates agitating mechanism 35.

In the boss 32 is formed a cylindrical

chamber 36, in which suitable packing 37 around the shaft 34 is placed. The packing here shown comprises alternately arranged rings 38 of bronze, and rings 39 which, as shown particularly in Fig. 6, are preferably of copper wire.

Into the outer end of the chamber 36 projects a sleeve 40 which is mounted to reciprocate within the boss 31, and which 10 terminates in a plate 41. Suitable bolts 42 through the plate 41 thread into the boss 31, and obviously by turning the bolts, the packing 37 can be adjusted as desired.

The agitating mechanism 35 comprises a 15 series of horizontally extending blades 43, which are securely mounted upon arms 44, as shown in Figs. 4 and 8. In the present embodiment four of these blades 43 are shown and the arms 44 are correspondingly 20 arranged in sets of four, being preferably integral with each other to make a support 45, which is keyed to the shaft 34, the number of blades and supports being varied according to the size and capacity of the stills.

25 The retorts B are similar in general construction to the stills A, comprising a metal tube 50 having flanges 51 and 52 at the ends thereof, and closed by caps 53 and 54, which have flanges 55 and 56, which rest against 30 the flanges 51 and 52, and are secured thereto by means of bolts 57, suitable packing 58 being provided.

35 The cap 53 has a central opening therethrough defined by an external boss 59, and an internal boss 60. Through the bosses 59 and 60 extends a pipe 61, the nozzle 62 of which bears against the inner end of the boss 60 which is internally formed to coincide with the outer form of the nozzle. 40 Around the pipe 61 behind the nozzle 62, there is provided in the bosses 59 and 60 a chamber 63 in which suitable packing 64 is provided. This packing may be similar to the packing previously described in connection with the stills A, and is held under compression by means of a sleeve 65 terminating in a plate 66. The position of the plate 66, with reference to the boss 59, may be regulated by means of bolts 67, so as to 50 adjust the packing 64.

55 In order to hold the pipe 61 in place with the nozzle 62 in close contact with the boss 60, suitable straps 68 are provided. These straps are mounted upon the boss 59 and are connected by a plate 69 in which a screw 70 is mounted. This screw bears against a hub 71 and the pipe 61, and by tightening the screw, the nozzle 62 is forced firmly into position and held there regardless of the 60 enormous pressure to which it is subjected.

Each still A is connected with the retort B above it by means of conduits 72. As here shown, two such conduits are provided, but it is obvious that the number can be 65 varied as is found desirable in order to in-

sure the safe and sufficient operation of this apparatus.

The chamber C is similar in formation to the stills A and retorts B, comprising a metal tube 73 having flanges 74 and 75 at the ends thereof and being closed by caps 76 and 77 provided with flanges 78 and 79, and held in place by bolts 80. Packing 81 between the flanges is also provided in order to seal the closures. 75

The chamber C is connected to both retorts by means of a plurality of conduits 82 and to both stills A by means of pipes 83, which are here shown of Y-formation. Rising from and connected to the collecting 80 chamber C are towers 84, each tower being provided with a suitable adjustable valve 85, which valve comprises a plate 86 carried by a stem 87 and held in a seat 88 by means of a suitable spring 89. This spring is located between a plate 90 carried on the valve stem 87 and a screw threaded plug 91 through which the valve stem 87 projects. By changing the position of the plug 91, the tension of the spring 89 can obviously be regulated. These towers are connected by pipes 92 to a single conduit 93 which leads to the condensers not shown. 90

Screwed to the lower side of each of the stills A adjacent the inner ends is a pipe 94, which is connected to a series of coils 95 resting against the side walls of the furnace D and enclosed by means of a plate 96. The purpose and function of these pipes will be disclosed herein below. 100

In order to remove the residue from the stills A, a sump 97 is provided in each still from the lowest point of which a pipe 98 leads to a trap 99, preferably of the intermittent or rotating type and having an outlet 105 100.

The furnace D comprises the side walls 101 connected by a top 102 and also by girders 103, which extend below and support the stills A, and in fact, the entire apparatus. In order to prevent the destruction of the girders 103 by reason of the heat of the fire box, these girders are imbedded in brick, as is shown in Fig. 1. Suitable pillars 104 of brick are formed along the center 115 of the furnace as shown in Figs. 1 and 3 in order to support the girders 103. The rear wall 105 of the furnace is provided with an angle slope 106 at the bottom and a projecting portion 107 having a smooth 120 angular under face 108, the slope 106 and face 108 being formed to deflect the heat against the ends of the stills A. A.

The inner ends of the retorts B extend beyond the rear wall 105 of the furnace as 125 shown particularly in Fig. 10, and are there provided with traps 109, which may be of any suitable intermittently actuated type, the operating mechanism being set in motion by the shafts 110. Mounted in each retort 130

B is a revolving scraper and agitator 111, which is similar in general construction to the agitator 35 in the stills A. Instead, however, of having the blades extending longitudinally in a straight line adjacent the walls of the retort the blades are twisted, as shown in the drawings, so that as a result, the agitator blades will cause any crust scraped from the walls of the retort to travel 10 toward the trap 109.

This agitator 111 comprises a plurality of blades 112 secured at one end to a solid disc 113, and at the other end to an annular plate 114. The plate 114 surrounds and bears upon 15 the inner end of the boss 60, which thus acts to support one end of the agitator 111. Rigidly secured to the center of the disc 113 is a shaft 115, extending outwardly through the cap 54, which is provided with a boss 20 116. In the boss 116 is formed a chamber 117, in which suitable packing 118 is placed around the shaft 115. This packing is preferably the same type as that previously described surrounding the shaft 35, and the 25 pipe 61. The packing 118 is duly compressed by means of a sleeve 119 having at its outer end a flange 120, suitable bolts 121 projecting through the flange 120 into the boss 116, permitting the adjustment of the 30 packing 118.

Between the disc 113 and the annular plate 114 are provided a series of floating rings 122 to which the blades 112 are secured. The rings 122 thus act to space the intermediate 35 portions of the blades 112 and at the same time do not interfere with the introduction of the crude oil under pressure from the nozzle 62. At the rear of the apparatus is provided an upright 123, in which the outer ends 40 of the shafts 110 and 115 are supported.

Mounted upon this upright 123 is a motor 124, by which the shafts 110 and 115 are rotated. The motor, which is of any suitable form, is provided with gear 125, which 45 meshes with a gear 126 on the shaft 115, and that gear in turn meshes with a gear 127 on the shaft 110. Thus the motor 124 causes the agitator 111 to rotate and also actuates the trap 109. The inner ends of 50 the retorts B are spaced from the stills A by columns 128 which may be replaced by conduits similar to the conduits 72 if desired.

As previously pointed out, the stills A, the retorts B in large part, and the chamber C, are substantially enclosed by the walls of the furnace. These walls, however, do not extend in front of the apparatus, and it is accordingly desired to close the furnace by the use of metal plates, as shown particularly in Fig. 2. This is best done by means of a T-beam 129, which is firmly secured to a boss 130 on the cap 76 and also to the base of the furnace in any suitable way. Metal plates 131 suitably shaped to 55 allow for the passage of the bosses 31 and

59, are rigidly secured to the flanges of the T-beam 129 and also to the top and side walls of the furnace, as shown particularly in Fig. 2, suitable packing being provided.

The outer end of each coil 95 passes 70 through the plate 131 and enters the rear of high pressure pumps 132. Into those pumps is also led a pipe 133, from a source of supply of crude oil, suitable cut off valves 134 and 135 being provided so that one or both of the pumps will be connected with the pipe 133. Fed by each of the pumps 132 is a pipe line 136, which is provided at its upper end with branches 137 leading to the pipe 61 at the retorts B. Suitable valves 80 138 are provided in the pipe line 136, to regulate the supply of crude oil from each pump. In the coil 95 between the plate 131 and the pump 132 is a valve 139 by which the feed from the coil to the pump is controlled.

At the outer end of each shaft 34 is provided a large gear 140, which gears are connected by means of the chain 141, so that both rotate in unison. Each shaft 34 is also provided with a sprocket 142, which is connected by means of a chain 143, with a sprocket 144 on the shaft 145 of the trap 99. A suitable motor 146 is connected to the other end of one shaft 145 so that by it, through the connecting gearing, the traps 99 and the agitators 35 of the stills are actuated. The high pressure pumps 132 are driven from a motor 147 by means of 90 sprocket and chain connections 148.

A thermometer 150 and gage 151 are connected with the stills A so that the temperature of the stills and the amount of crude oil therein can be determined easily. The furnace D may be heated in any suitable 100 manner but it has been found most convenient to employ gas or oil burners 152 in the fire box 153 supplied from the condenser by means not shown. The heat generated by the burners 152 rises around the stills A, retorts B and chamber C and passes off through the stack 154. Thus the walls of the retorts B are heated and function as cracker plates breaking up the crude oil sprayed against them from the nozzle 62.

The operation of this apparatus is as follows.

The cracking apparatus is filled with the crude oil to be treated by means of the pumps 132 from the intake pipe 133, passing through the pipe line 136, the branches 137, the pipe 61 and the nozzle 62 into the retorts B, and from the retorts B through the pipes 72 into the stills A which have already been heated by the burners 152. During the filling the agitators 35 are rotated, the traps 99 being kept closed in any suitable manner and valves 139 being closed when the gages 151 indicate that the stills are three-quarters full the valves 134, 135 110 120 125 130

are closed and the crude oil in the stills is heated to about 725° F. during which some light gases carrying gasoline will separate and rise to the chamber C through pipes 83. Since the pipes 94 are connected to the stills A it will follow that the coils 95 are filled and since they are separated from the intense heat of the fire box only by the metal plates 96, the oil in the coils will be heated to a higher temperature than that in the stills i. e. about 900° F. When the oil in the stills has reached a temperature of about 725° F., the valves 138 are opened, and the heated oil is allowed to pass into the pressure pump 132, whence it is fed up through the line 136 and sprayed by the nozzle 62 into the retorts B against the heated walls thereof. As the hot oil is sprayed by the nozzle against the hot walls of the retorts B, the light gases carrying gasoline rise through the pipes 82 into the collecting chamber C, and from there pass into the towers 84. The valves 85 are set at a predetermined tension, so that as soon as this is reached the plates 86 will be lifted and the gases pass through the pipe 92 into the condenser line 93.

The uncracked oil falls to the bottom of the retorts and returns through the pipes 72 to the stills A where it is whipped up by the agitators 35 and subjected to greater heat. At this step in the process, other gases will be cracked under the influence of the stirring heat and will rise through the pipes 83 directly to the collecting chamber C.

The remaining oil is retreated passing through the coils 95 to the pump 132 and being again sprayed into the retorts B. The repetition of this operation together with the intense heat results in further breaking up of the oil and the separation of more gasoline carrying gases. As the operation is continued the valves 134 and 135 are again opened to supply a certain amount of untreated oil so as to keep the amount being treated in the stills up to the predetermined amount. A certain percentage of the oil separates as an inert residue, which collects in the sumps 97 of the stills A, and passes off through the traps 99 which have again been set in motion.

One of the great dangers present in oil cracking apparatus is the formation on the inner walls of the retorts, and stills, of a carbon crust, which, if allowed to collect, will prevent the radiation of heat from the walls, so that as a result, the retorts and stills burn through. This fact is well known, and it is the general practice after a cracker has been in operation for a certain length of time, to stop operations and scrape the walls of the vessels very carefully in order to remove all of this carbon residue.

The provision in this apparatus of the

agitators 35 and 111 in the stills and retorts prevents the accumulation of this crust and keeps the inner walls clean, so that the necessity for stopping the operation of the apparatus which existed with the old cracking apparatus is obviated. The traps 109 at the inner ends of the retorts B reduce the amount of residue in the stills A, since the crust scraped from the walls by the agitators 111, and which would otherwise pass through the pipes 72 into the stills, is directly removed.

While one embodiment of this invention has been shown and described, I am not to be limited thereto since it is obvious that others may be made without departing from the spirit and scope of the invention as set forth in the following claims.

Having thus set forth one embodiment of my invention what I claim as new and for which I desire the protection of Letters Patent is—

1. A crude oil cracking apparatus comprising a still in which the oil to be cracked is heated, coils in which the oil passing from said still is superheated, a pump, a nozzle through which the oil from said coils is forced by said pump, a retort into which said nozzle opens, a collecting chamber, pipes connecting said chamber with said still and said retort through which the gasoline carrying gases cracked from the treated oil pass, a furnace enclosing said still, coils, retort, and pipes and means in said furnace for heating the enclosed parts.

2. In an apparatus of the type set forth in claim 1, an agitator in said still, means for actuating said agitator to keep the oil being heated constantly in motion and means for removing the inert uncrackable residue.

3. In an apparatus of the type set forth in claim 1, an agitator in said retort, means for actuating said agitator to scrape against the walls of the retort and prevent the formation of crust thereon.

4. In an apparatus of the type set forth in claim 1 an agitator in said retort, means for actuating said agitator to scrape against the walls of the retort and prevent the formation of crust thereon, one end of said retort extending beyond the walls of said furnace and a trap connected to the extended end of said retort whereby the crust scraped from the walls by said agitator is removed from the retort.

5. In an apparatus of the type set forth in claim 1, the firebox of said furnace being located below said still and said coils being installed along one side of said firebox, and a plate separating said coils from said heating means.

6. In an apparatus of the type set forth in claim 1, means for supplying crude oil to said pump independent of the supply from said coils.

7. A crude oil cracking apparatus comprising a still in which the oil to be cracked is heated, coils in which the oil passing from said still is superheated, a pump, a nozzle through which the oil from said coils is forced by said pump, a retort into which said nozzle opens, a collecting chamber, pipes connecting said chamber with said still and said retort through which the gasoline carrying gases cracked from the treated oil pass, a ¹⁰ furnace enclosing said still, coils, retort chamber, collecting chamber, and pipes and means in said furnace for heating the enclosed parts.

In testimony whereof I have affixed my ¹⁵ signature.

EMANUEL W. HARTMAN.
